UNITED STATES PATENT OFFICE

2,437,754

JETTY

George W. Rehfeld, Manhattan, Kans.

Application May 11, 1945, Serial No. 593,125

4 Claims. (Cl. 61—3)

1

This invention relates to jetties for protecting the banks of streams from erosion or for rebuilding such banks after erosion has occurred. The most satisfactory jetties for these purposes are those formed of structural members, for example, angle irons secured together in various forms and which may be provided with lacing to catch debris and retard the current sufficiently to effect deposit of silt carried by the stream. The structural members of such jetties must be of ample strength to withstand the force of flood waters and floating objects carried therewith. For practical purposes, jetties as heretofore constructed were restricted in size in order to obtain the desired strength and weight ratio, and to reduce difficulty of installation, labor costs, transportation charges, and to assure adequate bearing support thereof on the soils carrying the jetties. Consequently, such jetties have small covering area and are not effective in deeper waters.

It is, therefore, the principal purpose of the present invention to provide a jetty structure involving long length, light weight structural main members secured together intermediate their ends to form a plurality of outwardly diverging arms and legs so as to obtain a more efficient covering area for a given weight structure, and to provide relatively rigid spreader members for transmitting forces acting against any one of the arms to other arms and/or legs, whereby they cooperate in supporting the structure against the buffeting forces of flood waters.

Other objects of the invention are to provide a jetty structure that is readily adjusted to obtain the height or spread required for a given installation; to provide a jetty structure including a prop member having a relatively long leg for bracing the jetty against the force of the current and prevent overturning thereof; to provide a jetty structure wherein the arms are supported independently of the lacing so that the structure continues to function long after the lacing has given away to corrosion and breakage by floating objects; to provide a jetty structure forming a pocket directed into the current for facilitating entrapment and collection of debris thereby effecting more rapid rebuilding of the ground about the jetty; and to provide a jetty structure wherein the spreader members cooperate with the lacing to retard the current and to prevent settling of the jetty when installed on quicksand and loose soils.

In accomplishing these and other objects of the invention hereinafter pointed out, I have pro-

2

vided improved structure, the preferred forms of which are illustrated in the accompanying drawings wherein:

Fig. 1 is a perspective view of a jetty constructed in accordance with the present invention.

Fig. 2 is a plan view illustrating a line of jetties for protecting the bank of a stream.

Fig. 3 is a perspective view of a modified form of jetty.

Fig. 4 is a perspective view of one of the main members showing the arrangement of holes therein to provide for adjustment.

Fig. 5 is a perspective view of one of the spreader members.

Figs. 6 and 7 are diametric views illustrating adjustment of the jetty structure to fit a particular installation, Fig. 6 showing the main members adjusted to form a tall jetty having a narrow spread, and Fig. 7, a shorter jetty having a wide spread.

Referring more in detail to the drawings and first to the form illustrated in Figs. 1 and 2:

1 designates a jetty constructed in accordance with the present invention and which includes a plurality of main members consisting of cross members 6 and 7 and a prop member 8 which may be formed of relatively light weight angles having flanges 3 and 4. The flanges 3 and 4 are provided along the length thereof with openings 5 to thread lacing and secure spreader members of the jetty later described.

In the jetty illustrated the members 6 and 7 are arranged in crossing relation with the flanges 4 thereof in face to face contact and secured together at the crossing point by a fastening device such as a bolt 9 and on which the members are adapted to pivot for varying the spread of the ends thereof; for example, when adjusting the jetty structure to form a tall jetty or one having a large spread (see Figs. 6 and 7). The prop member 8 extends transversely of the member 7 and has one flange 4 secured in face to face contact with the flange 3 of the member 7 by a bolt 11, the attaching point being spaced from the fastening bolt 9 whereby the member 8 is adapted to fulcrum within the crotch 10 formed between the members 6 and 7 to thereby adjust the angle of the member 8 relative to the plane of the members 6 and 7 so as to vary the spread of the ends of the member 8 relative to the ends of the members 6 and 7. The members 6, 7, and 8 thus form a tripod-like structure having legs 12, 13, and 14 and outwardly and upwardly diverging arms 15, 16, and 17.

Since the main members are of relatively long length, the legs 12, 13 and 14 will have a relatively wide spread to assure firm support of the tripod-like structure upon the bed of a stream and the arms 15, 16 and 17 will have relatively wide spread to provide a maximum retard area with a minimum weight. Since the main members are formed of relatively light weight angle material, they are substantially flexible and the arms 15, 16 and 17 formed thereby may be incapable of withstanding the buffeting effects of a flood torrent and the logs and other debris carried therewith, even though the main members are laced with a wire lacing in accordance with customary practice. This is especially true when parts of the wire lacing become deteriorated through corrosion or breaks under the flood forces acting thereagainst.

In order to overcome this difficulty, the jetty is provided with spreader members 15 and 17 that are connecting the arms subjected to the more direct forces of the current and to connect the arms 15 and 17 by similar spreaders with one or more of the leg portions of the jetty.

In the form of the invention shown in Fig. 1, the arm 15 of the member 6 and the arm 17 of the member 8 are connected by a substantially rigid spreader member 19, preferably an angle and having one of the flanges 20 thereof lapping the arms 15 and 17 above the pivotal connections 9 and 11, the flanges of the member 19 being provided with openings 21 adapted to register with certain of the openings in the flanges of the members 6 and 8 to pass fastening devices such as bolts 22. It is thus obvious that any object striking the arm 17 on a side thereof in the longitudinal direction of the spreader will transmit a part of the shock therethrough to be absorbed by the arm 15 and that the arm 15 will act through the member 19 to assist in supporting the arm 17 and relieve tension on the lacing. The arms 15 and 17 are also preferably connected with the leg 13 of the member 7 by spreaders 23 and 24, which are preferably angles and having flanges thereof connected with the flanges of the main members by fastening devices 25 so that part of the force of a blow on the arms 15 and 17 is also absorbed by the leg 13.

In order that the main members and spreaders may be of standard length and yet provide an adjustable jetty, the ends of the spreaders are shown as being provided with a plurality of openings 21 in the flanges thereof and the flanges of the main members are also provided with a series of openings so that at least one opening in the ends of the spreader members may be registered with an opening in the main members to pass the fastening devices therethrough. All of the main members are of the same length and the attachment point for the member 8 may be located so that the leg 12 is longer than the legs of the other main members to provide a prop for preventing overturn of the jetty and to better resist the forces acting upon the jetty. If desired, the member 8 may be longer than the members 6 and 7 to provide a longer leg 12 as the case may require.

By inspection of Fig. 1, it will be noted that the arms 15 and 17 and the leg 13 cooperate with the spreader members 19, 23, and 24 to provide a substantially triangular pocket 26 located in facing relation with the direction of the current flow of a stream in which the jetty is installed.

In assembling the jetty, the members 6 and 7 are arranged in crossed relation and secured to-

gether by the fastening bolt 9 to form, for example, a cross, the relative width and height of which may be adjusted by pivoting the members on the bolt 9 (Figs. 6 and 7) so as to provide a relatively wide spacing for the legs 13 and 14 and arms 15 and 16 which results in a short height jetty (Fig. 7), or the spacing may be narrowed to provide a tall jetty (Fig. 6), as needed at the site of installation. For example, if the waters are low the jetty may be adjusted to obtain a wide spread (Fig. 7) to reduce the number of jetties required to cover a given area, or if the water is deep and taller jetties are required, the terminals of the arms and legs may be brought closer together to provide greater height. However, it is obvious that a jetty thus adjusted will have less spread, but this may be compensated for by increasing the number of jetties. The member 8 is then secured to the member 6 or 7 by the bolt 11 and adjusted so that the leg 12 has the desired spread relative to the legs 13 and 14. The spreader members 19, 23, and 24 are then secured to retain the main members 6, 7, and 8 in adjusted position and to form the substantially triangular-shaped pocket 26. The lacing wires 27 are applied by threading them through selected openings in the main members and the ends are secured, for example, by twisting them about the wires, as shown at 28.

In installing the jetties, they are connected in series by a cable 29 having one end anchored to a deadman 30 buried in the bank of the stream indicated at 31 (Fig. 2), the jetties being connected with the cable in any suitable manner. When installed, the jetties are located so that the pocket portions 26 thereof are directed into the flow of the current indicated by the arrows (Fig. 2), and they tend to collect floating debris and to retard the current sufficiently to cause settlement of soil for building up the bank and to protect the bank from further erosion and retain the stream in a desired course.

As the soil builds up around the jetty the wires may gradually deteriorate and corrode so that the wires may become broken under load of the debris; however, the jetty continues to serve its intended function since the spreader members 19, 23, and 24 have adequate strength to support the members of the jetty independent of the lacing wires. The spreader members being relatively rigid, tie the main members together under tension and also hold the main members apart under buffeting forces.

In the form of jetty illustrated in Fig. 3, a greater number of spreader members are used; for example, the arm 16 may be connected with the arms 15 and 17 by spreader members 33 and 34 and the legs 12, 13 and 14 may be connected with spreader members 35, 36 and 37, while the arms 15 and 16 may be connected with the leg 12 by spreader members 38 and 39 and the arms 16 and 17 may be connected with the leg 13 by spreader members 40 and 41. Thus, the number of leg and arm connecting spreaders in addition to those required to frame the pocket 26 may be varied to suit the particular installation.

When the spreader members are used as shown in Fig. 3, they may be adequate to provide the necessary retard of the current and the lacing may be omitted.

From the foregoing it is obvious that I have provided a jetty structure which involves long length, light weight structural members to produce a jetty having a relatively wide spread

and/or height depending upon the particular site in which the jetty is to be installed.

It is also obvious that the jetty while being of light weight and capable of substantial spread, the strengthening effect afforded by the spreaders adequately maintains the shape of the jetty, prevents disarrangement of the projecting arm and leg portions thereof under the severe forces to which jetties are ordinarily subjected.

What I claim and desire to secure by Letters Patent is:

1. A jetty including a plurality of structural members arranged one crossing another at a point intermediate ends of said members to provide upwardly and outwardly diverging arms and outwardly and downwardly diverging legs, means for connecting the members together in said crossing relation, and substantially rigid spreader members connecting a pair of immediately adjacent arms above the connecting means and said arms with an intermediate leg below the connecting means to support compression loads on said arms and legs and to form a pocket adapted to catch floating debris.

2. A jetty including a pair of members arranged one crossing the other at a point intermediate ends of said members to provide upwardly and outwardly diverging arms and outwardly and downwardly diverging legs, means for connecting the members together in said crossing relation, a prop member crossing one of said members to provide a leg cooperating with the legs of the pair of members to form a tri-point support for said jetty and an upwardly and outwardly diverging arm, pivot means for securing the prop member pivotally to said member crossed thereby for obtaining a desired spread and angle of inclination for the pair of members, a substantially rigid spreader member connecting the arm of the prop member with one of the arms of the pair of members above the crossing point of said crossed members, and similar rigid spreaders connecting said connected arms with the leg of the other member of said pair of members below the crossing point of said crossed members, said spreader members having adjustable connections with the members connected thereby to conform with the desired spread of said legs.

3. A jetty including a pair of main members arranged one crossing the other at a point intermediate ends of said members to provide up-

wardly and outwardly diverging arms and outwardly and downwardly diverging legs, means for connecting the main members together in said crossing relation, a prop member crossing one of said pair of main members to provide a prop leg cooperating with the legs of the pair of main members to form a tri-point support for said jetty and an upwardly and outwardly diverging arm, means for securing the prop member to said member crossed thereby, a substantially rigid spreader member connecting the arm of the prop member with one of the arms of the pair of members above the crossing point of said crossed members, and similar rigid spreaders connecting said last named arms with the leg of said other member of said pair of members below said crossing points.

4. A jetty including a pair of members arranged with one crossing the other at a point intermediate the ends of said members to provide upwardly and outwardly diverging arms and downwardly and outwardly diverging legs, means for connecting the members together in said crossing relation, a prop member crossing one of said members to provide a leg cooperating with the legs of the pair of members to form a tri-point support for said jetty and an upwardly and outwardly diverging arm, means for securing the prop member to said member crossed thereby, a substantially rigid spreader member connecting the arm of the prop member with the arm of said other member of the pair of members above the crossing points of said members, and similar rigid spreaders connecting the arm of the prop member and the arm of said other member with the leg of the member that is connected with the prop member.

GEORGE W. REHFELD.
